D18065

UNITED STATES PATENT OFFICE.

FREDERICK BRACKETT, OF WASHINGTON, DISTRICT OF COLUMBIA.

DESIGN FOR A CALENDAR.

SPECIFICATION forming part of Design No. 18,065, dated February 21, 1868.

Application filed January 23, 1868. Serial No. 261,664. Term of patent 3½ years.

To all whom it may concern:

Be it known that I, FREDERICK BRACKETT, a citizen of the United States, residing at Washington, in the District of Columbia, have invented and produced a new and useful Design for Calendars, of which the following is a specification, reference being had to the accompanying drawing, forming a part thereof, in which my invention is illustrated.

10 Heretofore calendars have usually been printed with the numbers of the days of the month either upon a plain background or in connection with figures, such as the different phases of the moon, &c.

15 The leading feature of my design consists in figures corresponding to the different army-corps badges used by the different army corps of the United States forces during the war of the rebellion. The numbers of the days of the

month are placed upon these different ornamental figures, producing an ornamental calendar-sheet of peculiar character. The representations of the corps-badges form an ornamental background for the numbers, thus producing a highly tasteful and ornamental calendar-sheet.

I claim—

The design for a calendar herein shown and described, the same consisting of an ornamental background composed of representations of 30 different army-corps badges having the ordinary numbers of the days of the month placed upon them.

FREDERICK BRACKETT.
